(57) **CLAIM**

We claim the ornamental design for a dispenser lever for refrigerator, as shown and described.

DESCRIPTION

FIG. 1 is a perspective view of a dispenser lever for refrigerator showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a reference view showing a state of use thereof. The parts shown by means of broken lines in the figures are not part of the claimed design.
